UNITED STATES PATENT OFFICE.

EDWARD R. WAGNER, OF MILWAUKEE, WISCONSIN, ASSIGNOR TO E. R. WAGNER MANUFACTURING COMPANY, OF NORTH MILWAUKEE, WISCONSIN, A CORPORATION OF WISCONSIN.

METAL DISK WHEEL.

Application filed March 4, 1922. Serial No. 541,256.

To all whom it may concern:

Be it known that I, EDWARD R. WAGNER, a citizen of the United States, residing at Milwaukee, in the county of Milwaukee and State of Wisconsin, have invented certain new and useful Improvements in Metal Disk Wheels, of which the following is a specification, reference being had to the accompanying drawing, forming a part thereof.

10 The main objects of this invention are to produce a light, strong and durable wheel of simple construction, from comparatively thin gage sheet metal, and generally to improve the construction and appearance of 15 metal disk wheels, particularly for children's vehicles.

It consists in the construction, arrangement and combination of parts as herein-after particularly described and pointed out 20 in the claims.

In the accompanying drawing like characters designate the same parts in the several figures.

Figure 1 is a side elevation of a wheel 25 embodying the invention, portions of the rim, front web disk and hub cap being broken away; Fig. 2 is a cross section of the wheel on the line 2—2, Fig. 1; Fig. 3 is a similar fragmentary section showing a rim of modified construction for a steel or metal tire; and Fig. 4 is a fragmentary face view 30 of the construction shown in Fig. 3.

Referring to Figs. 1 and 2, the wheel comprises two circular sheet metal disks or web 35 members 1, which are preferably symmetrically flared or bulged outwardly adjacent the center and to a less extent adjacent the rim, converging and then diverging from each other from the central portion towards 40 the rim of the wheel, as shown in Fig. 2.

The flaring shape of the disks braces the rim laterally, materially strengthens the wheel, provides a radially elastic and resilient connection between the rim and hub 45 which makes the wheel run smoother and increases its durability, and at the same time gives the wheel a more substantial and attractive appearance.

The disks or web members are formed 50 around central circular openings therein with outwardly projecting flanges 2 and 3. The flange 2 is formed with external cap retaining lugs or projections 4.

A cylindrical hub barrel 6, fitted at the

ends in the flanged openings in the web 55 disks or members 1, is formed adjacent its ends with outwardly projecting stop and spacing lugs 7, which engage with the inner sides of the disks 1 and properly space them from each other when the parts of the wheel 60 are assembled with the flanges 2 and 3 flush with the ends of the barrel. The hub barrel 6 may be made of sheet metal tubing drawn seamless or shaped from a flat blank.

The wheel may be constructed for use 65 with ball, roller or plain bearings.

When designed for use with ball bearings 9, as shown in Fig. 2, the hub barrel is formed with inwardly bent or projecting stop lugs 10, and the bearings are fitted in 70 the ends of the barrel against the lugs 10, as shown in Fig. 2.

For roller bearings, the lugs 10 are omitted, and the hub may be otherwise constructed for bearings of different kinds. 75

As shown in Fig. 2, the inner or one end of the hub is provided with a flanged bearing-retaining ring or dust guard 12, fitted over and secured on the flange 3 and extending inwardly over the edge of the flange and 80 end of the barrel.

At the outer or other end the hub barrel is closed to exclude dust and dirt and to give a finished and attractive appearance to the wheel, by a sheet metal cap 14, fitting over 85 the flange 2 and formed with an outwardly pressed annular bead or groove 15, or with internal recesses adapted to be sprung into and out of engagement with the lugs or projections 4. 90

The wheel is provided with a channel-shaped sheet metal rim 17, having out and inturned marginal folds 18, which are clasped over and tightly embrace the peripheral edges of the disks or web members 1, and form outwardly projecting tire-retaining flanges for confining a tire in the channel of the rim, such as a solid rubber tire 19, shown in Figs. 1 and 2. 95

The two web disks formed and spaced from each other as shown, and secured at their edges in the marginal folds of the rim, brace each other and form a firm support for the rim and tire, admitting of the use of comparatively light gage sheet metal in the construction of the wheel. 100

Referring to Figs. 3 and 4, showing a slight modification in the construction of the

rim for steel or metal tires, the rim 17' like the rim 17 for rubber tires, is formed with marginal folds 18, which are clasped over the edges of the web disks or members 1.

5 Between the marginal folds and flanges 18 the rim is preferably crowned, as shown in Fig. 3, to fit into the concave side of a concavo-convex steel or metal tire 19', the outer convex face of which projects outwardly beyond the flanges 18.

10 The metal tire, which is wrapped around the rim, is cut obliquely to its length at its meeting ends, as shown in Fig. 4, to form an oblique joint, and thus avoid the jolt or jar 15 of a straight transverse joint, particularly in running on pavements or hard roadways. The tire is preferably fastened adjacent its meeting ends to the rim by rivets 20, or it may be otherwise fastened thereto.

20 In other respects the construction of the wheel for metal tires is the same as that for rubber tires.

I claim:

1. A metal disk wheel comprising two 25 sheet metal web members formed with outwardly flanged central openings, a hub barrel fitted in said flanged openings and formed with outwardly projecting stop and spacing lugs engaging the inner sides of the 30 web members, and a sheet metal rim connecting the peripheries of the web members, the distance between the web members at

the hub barrel being greater than the distance between their peripheries at the rim.

2. A metal disk wheel comprising two 35 sheet metal web members formed with central outwardly flanged openings, a hub barrel fitted in said flanged openings and formed with outwardly and inwardly projecting lugs, the outwardly projecting lugs 40 engaging the inner sides of the web members, ball bearings fitted in the ends of the hub barrel against its inwardly projecting lugs, a flanged ring fitted over and secured to the central web flange on one side of the 45 wheel, and a cap removably fitted over the central web flange on the other side of the wheel.

3. A metal disk wheel comprising two circular sheet metal web members formed with 50 outwardly flanged central openings and bulged outwardly adjacent said openings and to a less extent adjacent their peripheries, the flange of one web member having an outward projection, a sheet metal cap 55 fitting over said flange and formed with a recess adapted to be sprung into engagement with the projection on said flange, and a flanged ring fitted and secured on the flange of the other web member and extending inwardly over the outer end thereof.

In witness whereof I hereto affix my signature.

EDWARD R. WAGNER.
